1 Claim

ABSTRACT OF THE DISCLOSURE

An improved battery terminal connection device including a cup configurated terminal integrally secured to a battery cable, a pressure ring fitted over the terminal for locking the same against a battery post.

This invention relates generally to battery post connections.

A principal object of the present invention is to provide an improved battery post connection which can be easily installed or removed from the battery post by means of a person's fingers and without the necessity of any tools.

Another object of the present invention is to provide an improved battery post connection which is corrosion proof.

Still another object of the present invention is to provide a battery post connection which has no nuts or bolts to corrode and which provides a positive electrical connection.

Other objects of the present invention are to provide an improved battery post connection which is simple in design, inexpensive to manufacture, rugged in construction, easy to use and efficient in operation.

These and other objects will be readily evident upon a study of the following specification and the accompanying drawing wherein:

FIGURE 1 is a perspective view of the present invention shown secured to a conventional storage battery;

FIGURE 2 is a cross-sectional view taken on the line 2—2 of FIGURE 1 and shown enlarged; and

FIGURE 3 is a view of a terminal member of the present device as viewed along line 3—3 of FIGURE 2.

Referring now to the drawing in detail, reference numeral 10 represents a battery terminal connector, according to the present invention, wherein there is a terminal member 11, and a pressure ring 12.

The terminal 11 comprises a cup configurated member made of lead alloy or other suitable metal, the terminal 11 having an opening 14 formed by generally tapering side wall 15 for purpose of receiving therein a battery post 17 of a storage battery 18. One end of a battery cable 19 is imbedded within the terminal 11, as shown in FIGURE 2 of the drawing so as to form a positive connection electrically therewith.

The pressure ring 12 comprises a cup configurated member formed from plastic material and includes a central opening 20 which is internally threaded as is shown at 21. The plastic pressure ring 12 is of generally cylindrical configuration and includes an upper end wall 22 that has a central opening 23 extending therethrough for purpose of allowing the battery cable 19 to protrude

2

therethrough. A re-enforcing wire 24 in the configuration of solid rings is imbedded within the pressure ring and is for the purpose of preventing the pressure ring from splitting open when in operative use.

As is shown in FIGURE 3, it is to be noted that the terminal member 11 may be provided with release slots 31 upon opposite sides thereof so as to allow the terminal to be depressed by the pressure ring around the battery post 17. Thus the release slots 31 provide space for folding around the battery post.

It will be noted that in FIGURE 2 of the drawing the assembly is shown with all the parts in proper relative positions to each other. In operative use, the terminal 11 having the imbedded battery cable 19 secured thereto is

fitted over the battery post 17, after which the pressure ring is brought down over the terminal member 11 and is rotated until the thread 21 thereof threads onto the terminal member and squeezes the same against the battery post as the pressure ring is threaded downwardly upon the terminal member. Thus a tight electrical connection is obtained.

I claim:

1. In a battery terminal connector, the combination of a terminal member, a pressure ring member, said terminal member being integrally secured to one end of a battery cable, said terminal member having means for being fitted over the battery post of a storage battery, said pressure ring being fitted over said terminal member, said terminal member comprising a cup configurated element made of lead alloy or other suitable metal threaded externally and having a generally conical configurated knurled opening therein for receiving said battery post therewith, said terminal member having an end wall to which said battery cable is connected, said terminal member being provided with a plurality of release slots upon opposite sides thereof to allow said terminal member to be squeezed around said battery post, said pressure ring comprising a cylindrically configurated plastic member having a generally tapered central opening, said opening being threaded internally, and said pressure ring having an end wall upon one end, said end wall having a central opening therein for receiving said battery cable therethrough, and said pressure ring being provided with a ring configurated re-enforcing wire imbedded therewith so to prevent spilling thereof when forced against said terminal member or squeezing the same against said battery post.
